Application December 9, 1933, Serial No. 701,694

9 Claims. (Cl. 26—46)

This invention relates to a method and to an apparatus for moistening fabrics, and more particularly for moistening hosiery which has been placed on a form or board preparatory to drying.

5 The present invention is especially adapted for use in connection with automatic hosiery driers of the type disclosed in the prior United States patent to Harry Coulston and Walter M. Schwartz, No. 1,126,619 dated January 26, 1915.

10 It is generally accepted in the art of hosiery finishing that a much better and more desirable finish is attained when the stockings, especially those composed wholly or in part of silk, natural or synthetic, are uniformly moistened immediately preceding drying than can be had when the stockings are not so preconditioned.

20 Many attempts have been made in the past to find a method and to provide an apparatus by which uniform preconditioning could be successfully and economically accomplished. These attempts may be classified in two groups, i. e. first, running moist-surfaced rollers over the fabric; and second, spraying a conditioning medium, such as steam and water, or either alone, in the vicinity of the stocking, usually within a suitable chamber.

25 The moist roll method is unreliable due to the inability to maintain the fabric-engaging surface of the roll or rolls uniformly moistened, hence the stockings are not uniformly moistened and when dry show variations in the finish between those parts which have not received equal moistening.

30 The spraying method likewise is unreliable because of the inability to prevent drops of the moistening medium from being projected against the stocking fabric and causing spotting thereof.

35 Another disadvantage attending the use of spraying systems in the past has been the clogging of the extremely fine holes, necessitated in the spray nozzles for atomizing the conditioning fluid, by small particle of foreign matter suspended in the fluid.

40 The spray nozzles heretofore have, to a greater degree, discharged the fluid directly against the fabric, in a direction either perpendicular or at some other various angle or angles relative to the plane of the fabric, and in some instances through a fine mesh screen or similar element interposed between the mouth of the nozzle and the fabric, to break up the fluid into the finest possible particles.

45 However, in all of such instances it has been impossible to prevent spotting, as the particles tend to collect on the ends or surfaces of the nozzles or intervening screens and then to be sud-

denly carried away by the flow of fluid from the nozzle and projected against the fabric, causing spotting.

5 Another objection to the spraying system, especially when steam is used, is that the steam being sprayed against or in close proximity to the fabric causes a bleeding of the dye from some portions and a concentration thereof at other portions of the fabric, thus the color of the finished fabric is not uniform.

10 In other instances, such as disclosed in the prior United States patent to Walter M. Schwartz and Frederick J. Kienel, No. 1,576,333 dated March 9, 1926, it has been attempted to create a moisture-laden region through which the 15 stockings are passed, but this system also employs a spray that projects steam vertically into a chamber adapted to receive the stockings. This system while it reduced it did not entirely eliminate spotting and bleeding and has a further inherent disadvantage in that the portions of the stocking in the upper part of the chamber become excessively moistened while the portions of the stocking in the lower part of the chamber are insufficiently moistened, causing shading in the 20 stocking.

25 The object of the present invention is to eliminate the above noted difficulties encountered in the moisteners of the prior art, and to provide a new method and a new apparatus by which uniform moistening of the hosiery is effectively and economically accomplished.

30 Primarily, the present invention consists in providing, placing, or relatively moving a moistening head, comprising an open-fronted box-like structure, substantially parallel to the surface of the fabric to be moistened, with the open front of the head structure adjacent the plane of the fabric surface, interposing a perforated fluid conductor in the head between the face 35 of the fabric and a rear wall or baffle surface of or in the head structure, and placing the perforations of the fluid conductor in that side thereof which faces toward the rear baffle surface within the head structure, whereby fluid escaping from the perforations, under pressure, is projected against and impinges upon the rear wall of the moistening head, or some other suitable baffle surface in the path of movement of the projected fluid as noted above, by which the fluid 40 is broken up and atomized, causing the fluid to hang in atmospheric suspension within the conditioning head to float or move, as a result of continuous impinging of the conditioning fluid 45 against the baffle surface in the head, toward the 50

open front of the head and into contact with the adjacently disposed surface of the fabric undergoing treatment.

By directing the fluid in a direction away from the open front of the head and consequently away from the fabric adjacent said open front, all tendency toward spotting is obviated, by reason of the carrying of any accumulation of moisture particles which may occur on the fluid conduit around the perforations thereof, away from the fabric and toward the rear of the head and against the above noted baffle surface by which such particles are broken up and by which, if such particles should fail to be broken up to an extent to permit of their free atmospheric suspension, such relatively large heavy particles are conducted to the base of the head and exhausted therefrom in a suitable manner.

By directing the conditioning medium, such as steam, or steam and water, away from the fabric all tendency toward bleeding is eliminated; and by concentrating the discharge of conditioning medium at and near the bottom of the moistener uniform moistening is obtained.

The construction and operation of the device by which the improved method of moistening fabrics is accomplished will be fully disclosed hereinafter, reference being had to the accompanying drawings; of which:

Fig. 1 is a longitudinal sectional elevation of a simple relatively small form of hand or mechanically operated structure adapted for movement in a plane approximately parallel to that of the surface to be conditioned;

Fig. 2 is a vertical longitudinal sectional elevation showing a pair of elongated heads adapted to be rigidly mounted at opposite sides of a path traversed by the hosiery forms prior to the entrance of the forms and stockings carried thereby into a suitable drying chamber;

Fig. 3 is a sectional plan view taken on the line 3—3, Fig. 2;

Fig. 4 is a greatly enlarged cross sectional view of the fluid conduit, showing the relation between the thickness of the wall and the diameter of the openings in the conduit by which clogging of the perforations is obviated;

Fig. 5 is a transverse sectional view of the moistening head with a baffle interposed between the fluid conduit and the rear wall of the head;

Fig. 6 is a similar view showing a flat baffle surface presented to the fluid by the rear wall of the head;

Fig. 7 illustrates the double head of Fig. 2 as being tilted and mounted on the front rail of an automatic drier of the type disclosed in each of the above noted patents;

Fig. 8 is a plan view showing the double head of Fig. 7 in section;

Fig. 9 is a view similar to Fig. 8, but showing the moistener mounted on the side rail of the drier in a true vertical position; and

Fig. 10 is a modification of the drip discharging means of one of the moistening heads shown in Fig. 2.

The conditioning head structure, illustrated at 1 in Fig. 1, is preferably of hollow conical, parabolical, or pyramidal form having its apex 2 curved, as in Fig. 1, or cut off flat and parallel to the plane x—x of the open front 3 of the structure, as shown at 2a, Fig. 6. In either case the side walls 4, 4 converge from the marginal edges of the open front 3 toward the rear surface 2 or 2a as the case may be.

Secured to one of the side walls 4, in the struc-

ture shown in Fig. 1, and projecting into the hollow interior of the head 1, substantially parallel to the open front 3, between the open front 3 and the rear wall 2, is a fluid conduit 5, in the rear side of which, i. e. the side facing toward the rear wall 2, is a relatively large opening or perforation 6.

It is preferable to form the conduit 5 of commercial copper tubing which, for example, in the quarter inch diameter size, has an extremely thin wall 7, as clearly shown in Fig. 4. The perforation 6 is preferably of a relative large size, i. e. several times as great in diameter as the thickness of the wall 7, hence no channel, having a length as great as or greater than the diameter of the hole 6, is formed, consequently clogging of the hole by particles of foreign matter suspended in the fluid passing through the pipe 5 and opening 6 is effectively obviated.

As shown in Fig. 1, the conditioning fluid, preferably steam and water, escaping from the opening 6, under suitable pressure, is directed against and impinges upon the inner surface 8 of the rear wall 2, which functions as a baffle and breaks up or atomizes the fluid globules into fine particles capable of remaining in atmospheric suspension within the head 1.

Continuous discharge of fluid from the opening 6, driving against the baffle surface 8, causes the suspended fluid particles to float toward the open front 3 of the head 1 into contact with the adjacently disposed surface of the fabric F, which is to be conditioned thereby. The relative flaring of the side walls 4, 4 permits of such great expansion of the fluid that the floating effect is effectively accomplished and forward driving of the fluid is avoided.

Any heavy particles or accumulation of particles forming on the pipe 5 around the opening 6 will either be carried away from the opening, 40 and away from the fabric, by the flow of fluid therethrough to be broken up against the baffle surface 8, or such accumulation will run down the pipe 5 and along the lower side wall 4 to be caught in a drip trough 9 provided by a vertical flange 10 formed on the forward edge of the lower side wall 4 and extending completely across the open front 3 of the head 1. The accumulation in the drip trough 9 is carried off from the head 1 by a suitable conduit 11.

The head 1 may be connected to and carried and operated by any suitable mechanism adapted to move the head 1 relative to the fabric or the head may be held stationary while the fabric is moved relative thereto in a plane adjacent and approximately parallel to the plane x—x of the open front 3 of the head.

Fig. 1 shows the head 1 as being provided with a handle 12 secured to the head and affording a support for the pipes 5 and 11 respectively, said handle including a valve 13 for manual operation when the head is in use and arranged to shut off the flow of fluid from the opening 6 in the pipe 5 when the head is not in use. In cases where the head is mechanically operated relative to the surface of the fabric F the valve 13 or its equivalent may be automatically operated to control the flow of fluid to the opening 6.

In Figs. 2, 7, 8 and 9, two conditioning heads 101, 101 are shown as being rigidly mounted in 70 opposed relation to each other at opposite sides respectively of the path of movement of a series of substantially vertically arranged stocking forms 20, in the case of Figs. 7 and 8 on the front rail 21 of an automatic hosiery drier of the type 75

disclosed in the above noted patents, and, in the case of Fig. 9, on one of the side or end rails 22 of the drier.

In each instance, the head 101 is elongated 5 vertical to a height equal to or exceeding the heights of the upper ends of the upstanding stocking forms 20 which pass through a slot 23 formed between the relatively spaced front planes $x-x$ and $x-x$ of the two heads 101, 101 respectively.

The stocking forms 20 in this type of automatic drier are usually provided with grippers 25, 25 (see Fig. 7), which are pivoted to the stems 26 of the forms at opposite sides thereof respectively, as 15 indicated at 27, 27, to be swung into gripping contact with the top or welt portion of the stocking F on the form, to hold the top or welt down firmly during the drying of the stocking, such grippers being clearly disclosed in the prior United States 20 patent to Harry Coulston, No. 1,190,119, dated July 4, 1916.

During the preconditioning or moistening of the stocking the grippers 25, 25 are open, as shown in Fig. 7, and the lower end walls 100, 100 of the heads 101, 101 respectively are disposed at angles corresponding to the angles of the open grippers, to permit the open grippers to pass outside the heads 101, 101 as the form 20 associated with the grippers passes through the slot 23 between the heads 101, 101.

In the heads 101, 101 the fluid pipes 105 are elongated and extend from the bottom walls 100, 100 to and beyond the top end of the slot 23 and direct fluid from their openings 106, 106, against 35 the inner baffle surfaces 108, 108 of the rear walls 102, 102 of the heads. The pipes 105, 105, to the greater extent of their lengths, extend parallel to the open fronts 103, 103 of the heads 101, 101 and at their lower ends bend toward and terminate 40 adjacent the fronts 103.

Parallel to the fronts 103, and lying in drip troughs 109, 109 formed by the front flanges 110, 110 and the bottom walls 100, 100 are open ended drip exhaust pipes 111, 111, which are provided 45 with vertical portions 112, 112. The vertical pipes 112 are bent at their upper ends 113, 113, to discharge into horizontally disposed intermediate drip troughs 114, 114, which catch the drip or condensation which trickles down the insides of 50 the flaring side walls 104, 104.

The drip concentrated in the troughs 114, 114 is discharged from the heads 101, 101 by drain pipes 115, 115 to a level below the lower edge of the fabric F.

The pipes 105, 105 are connected at their upper ends to a feed pipe or manifold 116 by which the two pipes are fed with fluid under pressure and under control of a valve 117 from a pipe 118 which is connected to a suitable source (not shown).

The perforations 106, 106 are equally spaced 60 throughout the greater portion of the length of each pipe and toward the lower ends of the pipes the holes 106 are relatively closer together than at the upper portion of the pipe, to keep the lower portions of the heads 101, 101 filled with the floating atmospherically suspended conditioning medium which has a natural tendency to rise in the heads.

Connected to the fluid supply pipe 118 is a pipe 70 119, flow from which is controlled by a valve 120. Connected to the second side of the valve 120 is a pair of small pipes 121, 121, which project into the heads 101, 101 respectively and therein pass downwardly, between the pipes 105, 105 and the opposite faces of the fabric F respectively,

to the lower drip troughs 109, 109, wherein the ends of the pipes 121, 121 project into the open ends of the drip exhaust pipes 111, 111 and function as injectors to draw the drip from the troughs 109 into the pipes 112 and then raise the drip in the pipes 112 to effect discharge thereof into the upper drip troughs 114.

In Fig. 10 the injector pipes 121a are connected directly to the lower ends of the fluid pipes 105, but the previously described arrangement is 10 preferable as the discharge of the drip from the troughs 109 by flow of fluid through the injector pipes 121 may be independently controlled with respect to the flow of fluid through the fluid pipes 105, by manipulation of the valves 117 and 120. 15

The upper portions of the heads 101, 101 and the slot 23 are covered by a hood 125 which bridges the upper end of the slot 23, the fluid being carried off by a conduit or exhaust pipe 126 which may be connected to any suitable exhaust 20 fan, etc. A damper 127 may be provided to control the rate of exhaust of the floating fluid from the heads 101.

The operation of the devices of Figs. 2, 7, 8 and 9 is substantially the same as the operation of the 25 device shown in Fig. 1. The fluid passing through the pipes 105, 105 is directed by the rearwardly pointing openings 106, 106 against the baffle surfaces 108, 108 and expands by reason of the flaring relation of the side walls 104, 104 so that the 30 fluid particles float toward the fronts 103, 103 of the heads 101, 101 and contact the stocking fabric F on opposite sides of the forms 20 simultaneously, the accumulation of condensed steam or water collected in and by the drip troughs 109, 109 and 35 114, 114 being discharged from the heads and thereby being prevented from spotting the hosiery.

Fig. 5 shows a flat baffle plate 18 disposed within the head 1 in spaced relation to the back wall 2 and while the surface of this baffle against which the fluid discharged from the pipe 5 impinges is shown as being flat it may be either concaved or convexed as desired for spreading or concentrating the fluid in the back part of the head 45 during expansion and before floating toward the open front 3 of the head.

The fluid discharge openings 106 in the lower portions of the pipes 105, as noted above, may be closer to each other than those in the upper 50 portions of the pipes and are preferably drilled at an angle so that they direct their discharges toward the bottoms of the heads 101, to concentrate the fluid in the bottoms of the heads to offset the natural tendency of the fluid to rise. 55

We claim:

1. A fabric-moistening device comprising a pair of laterally spaced chambers providing a vertical fabric-receiving slot therebetween and having openings adjacent the opposite sides of the 60 slot respectively, means in said chambers remote to the openings for effecting atmospheric suspension of a moistening medium within the chambers and causing said suspended medium to float in opposite directions toward the slot into contact with the fabric therein, and a hood bridging the upper end of the slot for collecting suspended medium rising from the chambers at 65 opposite sides of the fabric.

2. A fabric-moistening device comprising a 70 chamber having a vertically elongated face opening adjacent which the fabric is positioned, side walls converging from the side margins of the opening toward an apex remote to the opening, a bottom wall inclined from the lower margin 75

of said opening inwardly of the chamber, a fluid pipe extending vertically intermediate the plane of the opening and the apex and having a series of vertically spaced openings for projecting fluid toward the apex at a plurality of vertically spaced planes respectively, a baffle surface intercepting the projected fluid and effecting atmospheric suspension of the fluid and causing the suspended fluid to float toward the opening and into contact with the fabric, and a drip trough formed at said bottom margin of the opening by said inclined bottom wall for collecting non-suspended fluid.

3. A fabric-moistening device comprising a chamber having a vertically elongated face opening adjacent which the fabric is positioned, side walls converging from the side margins of the opening toward an apex remote to the opening, a bottom wall inclined from the lower margin of said opening inwardly of the chamber, a fluid pipe extending vertically intermediate the plane of the opening and the apex and having a series of vertically spaced openings for projecting fluid toward the apex at a plurality of vertically spaced planes respectively, a baffle surface intercepting the projected fluid and effecting atmospheric suspension of the fluid and causing the suspended fluid to float toward the opening and into contact with the fabric, a drip trough formed at said bottom margin of the opening by said inclined bottom wall for collecting non-suspended fluid, a discharge pipe having an opening disposed in said drip trough, and a pipe injecting live fluid into said discharge opening for drawing the non-suspended fluid into said discharge pipe.

4. A fabric-moistening device comprising a chamber having a vertically elongated face opening adjacent which the fabric is positioned, side walls converging from the side margins of the opening toward an apex remote to the opening, a bottom wall inclined from the lower margin of said opening inwardly of the chamber, a fluid pipe extending vertically intermediate the plane of the opening and the apex and having a series of vertically spaced openings for projecting fluid toward the apex at a plurality of vertically spaced planes respectively, a baffle surface intercepting the projected fluid and effecting atmospheric suspension of the fluid and causing the suspended fluid to float toward the opening and into contact with the fabric, a drip trough formed at said bottom margin of the opening by said inclined bottom wall for collecting non-suspended fluid, a drip trough on the converging side walls above the first said drip trough, a discharge pipe having an opening disposed in said lower drip trough, a pipe injecting live fluid into said discharge opening for drawing the non-suspended fluid into said discharge pipe and for passing the drip fluid through the discharge pipe into said upper trough, and means for exhausting said drip fluid from said upper trough.

5. A fabric-moistening device comprising a chamber having a vertically elongated face opening adjacent which the fabric is positioned, vertical side walls and a bottom wall constituting margins of said opening, a fluid pipe extending vertically within the chamber adjacent the plane of the opening and having a series of vertically spaced openings for projecting fluid toward the rear of the chamber at a plurality of vertically spaced planes respectively, a baffle surface intercepting the projected fluid and effecting atmospheric suspension of the fluid and causing the suspended fluid to float toward the opening and into contact with the fabric, a drip trough in the bottom of the chamber for collecting non-suspended fluid, a discharge pipe having an opening disposed in said drip trough, a pipe constituting an extension of said fluid pipe extending from said fluid pipe into the opening of said discharge pipe for injecting live fluid into said discharge pipe opening for drawing the non-suspended fluid into said discharge pipe, and means for in-

5 and into contact with the fabric, a drip trough in the bottom of the chamber for collecting non-suspended fluid, a discharge pipe having an opening disposed in said drip trough, and a pipe injecting live fluid into said discharge pipe opening for drawing the non-suspended fluid into said discharge pipe.

6. A fabric-moistening device comprising a chamber having a vertically elongated face opening adjacent which the fabric is positioned, vertical side walls and a bottom wall constituting margins of said opening, a fluid pipe extending vertically within the chamber adjacent the plane of the opening and having a series of vertically spaced openings for projecting fluid toward the rear of the chamber at a plurality of vertically spaced planes respectively, a baffle surface intercepting the projected fluid and effecting atmospheric suspension of the fluid and causing the suspended fluid to float toward the opening and into contact with the fabric, a drip trough in the bottom of the chamber and an upper drip trough spaced above said bottom drip trough for collecting non-suspended fluid, a discharge pipe having an opening disposed in the said bottom drip trough and an outlet in said upper trough, and a pipe injecting live fluid into said discharge pipe opening for drawing the non-suspended fluid from the bottom trough into said discharge pipe and discharging said fluid into the upper trough, and means for exhausting said fluid from said upper trough.

7. A fabric-moistening device comprising a chamber having a vertically elongated face opening adjacent which the fabric is positioned, vertical side walls and a bottom wall constituting margins of said opening, a fluid pipe extending vertically within the chamber adjacent the plane of the opening and having a series of vertically spaced openings for projecting fluid toward the rear of the chamber at a plurality of vertically spaced planes respectively, a baffle surface intercepting the projected fluid and effecting atmospheric suspension of the fluid and causing the suspended fluid to float toward the opening and into contact with the fabric, a drip trough in the bottom of the chamber for collecting non-suspended fluid, a discharge pipe having an opening disposed in said drip trough, a pipe injecting live fluid into said discharge pipe opening for drawing the non-suspended fluid into said discharge pipe, and means for independently controlling the flow of fluid through said fluid pipes.

8. A fabric-moistening device comprising a chamber having a vertically elongated face opening adjacent which the fabric is positioned, vertical side walls and a bottom wall constituting margins of said opening, a fluid pipe extending vertically within the chamber adjacent the plane of the opening and having a series of vertically spaced openings for projecting fluid toward the rear of the chamber at a plurality of vertically spaced planes respectively, a baffle surface intercepting the projected fluid and effecting atmospheric suspension of the fluid and causing the suspended fluid to float toward the opening and into contact with the fabric, a drip trough in the bottom of the chamber for collecting non-suspended fluid, a discharge pipe having an opening disposed in said drip trough, a pipe constituting an extension of said fluid pipe extending from said fluid pipe into the opening of said discharge pipe for injecting live fluid into said discharge pipe opening for drawing the non-suspended fluid into said discharge pipe, and means for in-

dependently controlling the flow of fluid through said fluid pipes.

9. A hosiery-moistening device comprising a pair of laterally spaced and opposed open sided chambers providing a slot therebetween for receiving a stocking mounted on a form, means in said chambers for atmospherically suspending and floating a moistening medium in opposite directions in said chambers respectively toward

said slot and into contact with the stocking therein, said chambers having inclined bottoms respectively paralleling open angularly disposed stocking grippers carried by the stocking form and normally closed to grip the stocking, permitting said open grippers to pass outside said chambers during moistening of the stocking.

CHARLES T. GRIFFITH.
